 a corporation of Pennsylvania

Application May 7, 1941, Serial No. 392,400

17 Claims. (Cl. 175—335)

This invention relates to electrical control systems, and, more particularly, to a novel circuit-controlling apparatus for making and breaking an electrical circuit without producing objectionable arcing at switching contacts.

The principal object of the invention is to provide a simple apparatus of this general character which may be constructed economically and which is highly efficient in operation.

A more specific object of the invention is to provide a novel apparatus wherein the starting and stopping of current flow in a circuit to be controlled is effected by means of an electronic device whose conductivity is controlled in a predetermined manner.

Another object of the invention is to provide an apparatus of the stated character employing a grid-controlled rectifier tube or tubes in a novel manner to start and stop the current flow in a circuit or circuits being controlled.

A further object of the invention is to provide a novel record-controlled apparatus for controlling the energization of one or more electrical devices.

The invention is particularly adapted for use in a yarn-selecting machine having selectable electromagnets or solenoids, and, therefore, a further object of the invention is to provide a novel yarn-selecting machine wherein the electromagnets are controlled without producing arcing at the magnet-selecting contacts.

Since the invention is particularly adapted to a yarn-selecting machine and in its more limited aspect relates to the control of such a machine, it will be described with reference to this specific adaptation, although it is to be understood that the invention is not thus limited but is capable of general use.

In the accompanying drawings:

Fig. 1 illustrates one electromagnetically-controlled unit of a yarn-selecting machine to which the invention is applied;

Fig. 2 is a diagrammatic illustration of the electrical system employed according to the invention; and

Fig. 3 is an enlarged illustration of the record-controlled contact-making device.

In Patent No. 2,126,634, issued to R. W. Homan on August 9, 1938, there is fully illustrated and described a yarn-selecting machine employing electromagnets which are selectively energized to effect the yarn-selecting function. Each magnet controls one section of the machine, and each section comprises a plurality of yarn carriers supported on a common track. Each time the elec-

tromagnet is energized, it operates a certain mechanism to release one of the yarn carriers, as fully described in the said patent. In its specific adaptation to such a machine, the present invention has for its object the provision of novel means for controlling the electromagnetically-operated mechanism of each section of the machine.

In Fig. 1, there is illustrated one section of a yarn-selecting machine constructed according to the above-mentioned Homan patent with certain modifications to adapt the machine for use with the present invention. As in the machine of the Homan patent, there are provided a plurality of 10 yarn-carriers 1 through which the yarn strands 2 loosely extend. The yarn carriers are slidably mounted on a horizontal track comprising stationary rods 3. The release of the yarn carriers is controlled by a rotatable shaft 4 extending from a vertical plate 5 on carriage 5a which moves along the rods 3. Near one end of the shaft 4, there is provided a pin 6 which is normally misaligned with slots in the yarn carriers. When the shaft is rotated, the pin is brought into 15 alignment with the carrier slots and one of the yarn carriers is released by virtue of the movement of carriage 5a, the remaining yarn carriers being retained due to the immediate return of shaft 4 to its normal position. The shaft 4 is rotatable through a predetermined angle by 20 means of a spring-biased rack-bar 7 slidably carried by carriage 5a and having a gear-rack portion meshing with a pinion on the shaft. All of 25 the above-described mechanism is embodied in 30 the machine of the Homan patent to which reference may be had for a detailed disclosure.

The rack-bar 7 carries a pivoted latch member 8 which is normally maintained in alignment with the rack-bar by a leaf spring 9 attached to the bar at 10. A shaft 11 is rotated at a constant speed and is provided with a series of shoulders 12. When the latch member 8 is in the normal position shown, it is out of the path of the shoulders 12. Energization of an electromagnet 13 serves to depress the latch member 8 into the path of the rotating shoulders 12, whereupon one of the said shoulders engages the shoulder 14 of the latch member moving the rack-bar 7 to the left, as viewed in Fig. 1, until the latch member is raised by its engagement with a cam member 15 mounted on plate 5. In the meantime, the electromagnet will have been deenergized since it is energized only for a short interval.

To effect the above-described operation, the electromagnet has a hinged armature 16 which is

normally in a raised position. A non-magnetic separator 17 prevents the armature from sticking to the magnet core. The armature 16 carries an adjustable rod 19, the lower end of which is adapted to engage the latch member 8 to depress the same against the action of spring 9 whenever the armature 16 is attracted by the electromagnet. The upper end of rod 19 is adapted to abut against an adjustable stop 20 carried by bracket 21.

As stated previously, the complete machine comprises a plurality of sections of the character illustrated in Fig. 1. For example, in a specific embodiment of the machine, forty-eight of such sections are employed, there being a corresponding number of electromagnets for controlling the operation. However, since the sections are superposed with respect to one another, the shaft 11 is common to all of them, the shoulders 12 extending vertically throughout the entire height of the superposed sections of the machine. The shaft 11 may be driven by the motor which actuates other moving parts of the machine, as disclosed in the Homan patent.

For the purpose of the present invention, it is unnecessary to illustrate in greater detail the yarn-selecting machine to which the invention is particularly adapted. The illustration of Fig. 1 is deemed sufficient for the present purpose in view of the complete disclosure of a machine of this character in the Homan patent.

Referring now to Fig. 2, there is illustrated the novel circuit-controlling means provided by this invention which is adapted to control the energization of the electromagnets in a machine of the character above described, but which is also capable of general use for controlling the energization of one or more electrical devices. The windings of the electromagnets, which in this instance are the devices to be energized, are represented at 22. Only two of the windings are shown in full, the arrowhead connections 23 representing connections to other electromagnets. Of course, there may be any number of the electromagnets, as previously mentioned. A common conductor 24 serves as one of the current-supply connections to the electromagnets, the individual connections to the magnet windings being connected in parallel to the conductor 24. A second common current-supply connection for the electromagnet windings is shown at 25. One end of conductor 25 is connected to a ground point 26, while the opposite end is electrically connected to a metal roll 27. The connection to the roll is diagrammatically illustrated, but it will be understood that this connection may be of any suitable type. For example, it may comprise a brush engaging the rotatable roll. Contact fingers or brushes 28, to which the respective magnet windings are connected, engage the cylindrical surface of the metal roll 27. The current-supply connections to the magnet windings are selectively completed by means of a pattern or record which may take the form of a perforated insulating sheet, as described in the above-mentioned patent. In Fig. 3, there is an enlarged showing of the contact-making roll 27 over which the record or pattern sheet 29 passes. The roll 27 is rotated at a predetermined speed, for example, by means of a motor employed in the machine, as described in the Homan patent. The perforations in the record or pattern sheet are equally spaced longitudinally of the sheet, and these holes are of a predetermined size so that the current-supply connections for the electro-

magnets are selectively energized during successive intervals of very short duration.

In accordance with the present invention, the selective energization of the electromagnet windings is effected by means of the apparatus now to be described without making or breaking the current-supply connections while current is flowing therein. The current input conductors 30 are representative of any suitable current-supply source, and in the specific apparatus illustrated, these conductors are assumed to be connected to an alternating current source, for example, the usual commercial source of sixty cycle current of suitable voltage, such as 110 volts. A full-wave rectifier comprising transformer 31 and electron discharge tubes 32 and 33 is adapted to supply unidirectional current to the electromagnet windings. As is usual in this type of rectifier, the transformer 31 has two secondary windings 34 and 35, and the filaments of the tubes are connected across the low voltage winding 34, while the tube anodes are connected to opposite terminals of the relatively high voltage winding 35. As is also customary, each of the secondary windings is center-tapped and the rectified current output is derived from the leads 24 and 36 connected to the center taps of the said windings. It will be noted that the conductor 36 is connected to the grounded point 26. It will be understood that the tubes 32 and 33 are adapted to operate on alternate half cycles of the alternating current.

The tubes 32 and 33 are grid-controlled rectifier tubes and these tubes are preferably thyratrons of the type known as 2A4G. Such a tube is characterized in that current will flow between its anode and cathode when the grid voltage is zero with respect to the cathode. Therefore, to prevent anode-to-cathode conduction, the grid must be made negative with respect to the cathode during the time that the anode is at a positive potential. In the circuit illustrated, the tubes are rendered normally-non-conductive by connecting the grid of each tube to the anode of the other tube through a suitable current-limiting resistor 37 or 38. Condensers 39 and 40 are also provided in these connections for a purpose which will be explained presently.

Disregarding the condensers 39 and 40 for the moment, it will be seen that during one-half cycle of the alternating current, the anode of tube 32 will be positively charged, while the anode of tube 33 is negatively charged. At such time, therefore, the tube 32 is conditioned for anode-to-cathode conduction, but the grid of the tube is negatively biased by virtue of its connection to the terminal of secondary winding 35 opposite the terminal to which the anode is connected. Therefore, the tube is rendered non-conductive. During the other half cycle of the supply current, tube 33 is conditioned for anode-to-cathode conduction, but its grid is negatively biased in a similar manner.

The tubes 32 and 33 are rendered conductive at predetermined times by means of the contact roller 41 which serves to reduce the potential of the grid of each tube substantially to zero with respect to the cathode. To this end, the roller 41 is formed of metal, and it has an insulating section 42 which may cover one-half of the cylindrical surface of the roller. The grids of the tubes are connected by means of conductors 43 and 44 to contact brushes 45 and 46 engaging the cylindrical surface of the roller. The metallic portion of the roller is connected to the

grounded point 26 by means of conductor 47. It will be seen, therefore, that as the roller 41 rotates, the grids of tubes 32 and 33 are connected intermittently to the tube cathodes when the brushes 45 and 46 engage the conductive portion of roller 41. This connection of the grids to their respective cathodes is via the conductors 43 and 44, the conductive portion of the roller 41, conductors 47 and 36, and the secondary winding 34. The voltage across winding 34 may be disregarded in this instance.

The roller 41 is rotated in coordination with the roller 27 and the perforated sheet 29 so that the tubes 32 and 33 are rendered conductive within the time intervals during which the connections to the electromagnets are completed. The roller 41 should be so designed and should be rotated at a predetermined speed such that the brushes 45 and 46 engage the conductive portion of the roller after contact has been made with one of the brushes 28 through a perforation in the record sheet 29, and the brushes 45 and 46 leave the conductive portion of roller 41 before the contact is interrupted at the brush 28. The roller 41 may be properly coordinated with roller 27 by suitable gearing 48 and the two rollers may be driven from the same source of power.

Thus, it will be seen that the current-supply connections to the electromagnet windings 22 are not made or broken while current is flowing in such connections, the current flow being started after a connection is made and being stopped before a connection is broken, through the action of the contact roller 41 which functions to start and stop the rectifier tubes 32 and 33. In this manner, pitting and burning of the contacts at the roller 27 is prevented. Since the load circuit comprising the electromagnet windings is an inductive D. C. circuit, serious pitting and burning of the contacts would result from the opening and closing of the circuit under load. This has been a serious defect of prior devices of this character. By the present invention, this defect is eliminated.

It is important to note that the contact roller 41 is only required to handle very small currents in non-inductive circuits, and, therefore, no pitting or burning will take place. Moreover, the resistors 37 and 38 serve to limit the current to contact roller 41, as well as to the grids of the tubes.

If the load devices supplied by the rectifier tubes were entirely non-inductive, it would be unnecessary to use the condensers 39 and 40. However, the load devices are inductive and the presence of their inductance in the load circuit tends to disturb the phase relation between the grid and anode voltages of the rectifier tubes. As a result, the anodes tend to swing positive before the negative voltage on the grids has become large enough to prevent conduction. The condensers 39 and 40 prevent this condition from obtaining. Since the grid of each tube goes positive when its anode is negative, grid rectification takes place in the tube and the associated condenser is charged by grid current flowing through the resistance 37 or 38 and the grid-cathode path within the tube. The voltage which is thus produced across each condenser is in such a direction as to increase the normal negative A. C. bias on the grids. Thus, there is provided a novel means utilizing grid rectification action of the tubes to provide a negative D. C. bias on the grids during the intervals when the tubes are not rendered conductive by the contact roller 41.

In one physical embodiment of the invention which was found to operate satisfactorily, the electrical elements were as follows:

Tubes 32 and 33 were of the type above mentioned.

The transformer 31 was adapted for 110 volts on its primary and produced 220 volts across secondary 35 and 2.4 volts across secondary 34.

The resistors 37 and 38 were 1,000 ohm, 5 watt, wire-wound resistors.

The condensers 39 and 40 were of the paper tubular type, each having a capacitance of 0.01 microfarad.

From the above description, it will be seen that the invention provides a novel apparatus for controlling the energization of one or more electrical devices without making and breaking the connections to such devices while current is flowing therein. Obviously, the invention is not limited to the specific form illustrated. The contact-making roller 27 and the associated record sheet are representative of any device for completing the connections to an electrical device during a predetermined interval. Obviously, this function may be performed by other specific forms of contact-making devices. For example, the connections to a device to be energized during a predetermined interval or during recurring intervals could be operated by means of a cam-actuated switch, such as is commonly employed in electrical devices. Regardless of the nature of the mechanism for completing the connections to the device or devices to be energized, the contact roller 41 may be coordinated with such mechanism so as to effect starting and stopping of the current flow within the interval during which the connections are made.

It will be apparent also that the invention is capable of use in a wide variety of electrical devices. For example, it may be employed in connection with sign lighting where it is desired to operate one or more circuits intermittently. Hence, the electromagnet windings 22 are to be considered as representative of any electrical device or devices to be energized during a predetermined interval or intervals.

It will be understood, therefore, that the invention is not limited to the specific disclosure, but is capable of various modifications within the scope of the appended claims.

I claim:

1. In a circuit controlling apparatus, an electrical device whose energization it is desired to control, current supply connections for said device, contact making means for completing said connections during a predetermined interval, a source of alternating current, rectifying means including a grid-controlled rectifier tube for energizing said device from said source via said connections, means for applying a negative biasing potential to the grid of said rectifier tube of a magnitude to render the tube normally non-conducting, and means for rendering said tube conductive after the commencement of said interval and for permitting said biasing potential to become effective before the termination of said interval, whereby said device is energized without making or breaking said connections while current is flowing therein.

2. In a circuit controlling apparatus, an electrical device whose energization it is desired to control, current supply connections for said device, contact making means for completing said connections during a predetermined interval, a source of energizing current, means including a

grid-controlled electron discharge tube for supplying current from said source to said device, means for causing the grid of said tube to draw current, means responsive to the grid current flow for biasing the grid of said tube so as to render it non-conductive, and means for rendering said tube conductive after the commencement of said interval and for permitting the grid bias to become effective before the termination of said interval, whereby said device is energized without making or breaking said connections while current is flowing therein.

3. In a circuit controlling apparatus, an electrical device whose energization it is desired to control, current supply connections for said device, contact making means for completing said connections during recurring intervals, a source of alternating current, a full-wave rectifier for supplying current to said connections, said rectifier including a pair of grid-controlled rectifier tubes arranged to operate on alternate half cycles of the alternating current from said source, and means for rendering said tubes operative after the commencement of each said interval and for rendering said tubes inoperative before the termination of each interval, whereby said device is energized recurrently without making or breaking said connections while current is flowing therein.

4. In a circuit controlling apparatus, an electrical device whose energization it is desired to control, current supply connections for said device, record-controlled contact making means for completing said connections during recurring intervals, a source of alternating current, a full-wave rectifier for supplying current to said connections, said rectifier including a pair of grid-controlled rectifier tubes arranged to operate on alternate half cycles of the alternating current from said source, and means operable coordinately with said record-controlled means for varying the grid potential of said tubes so as to render the tubes operative after the commencement of each said interval and to render the tubes inoperative before the termination of each interval, whereby said device is energized recurrently without making or breaking said connections while current is flowing therein.

5. In a circuit controlling apparatus, an electrical device whose energization it is desired to control, current supply connections for said device, record-controlled contact making means for completing said connections during recurring intervals, a source of alternating current, a full-wave rectifier for supplying current to said connections, said rectifier including a pair of grid-controlled rectifier tubes arranged to operate on alternate half cycles of the alternating current from said source, means for causing the grids of said tubes to draw current, means responsive to the grid current for biasing the grids of the tubes so as to render them non-conductive, and means for rendering said tubes conductive after the commencement of each said interval and for permitting the grid bias to become effective before the termination of each interval, whereby said device is energized recurrently without making or breaking said connections while current is flowing therein.

6. In a circuit-controlling apparatus, an electrical device whose energization it is desired to control, current-supply connections for said device, record-controlled contact-making means for completing said connections during recurring intervals, a source of alternating current, a full-

wave rectifier for supplying current to said connections, said rectifier including a transformer and a pair of grid-controlled rectifier tubes connected to said transformer so as to operate on alternate half cycles of the alternating current from said source, said transformer including a secondary winding and said tubes having their anode elements connected to opposite terminals of said secondary winding, a condenser connected between the grid of one tube and the terminal of said winding opposite the terminal to which the anode of said tube is connected, a second condenser connected between the grid of the other tube and the terminal of said winding opposite the terminal to which the anode of said other tube is connected, whereby said tubes are rendered non-conductive by biasing voltages established across said condensers due to grid rectification in the tubes, and means for nullifying the effect of said biasing voltages to render said tubes conductive after the commencement of each said interval and for permitting the biasing voltages to become effective before the termination of each interval, whereby said device is energized recurrently without making or breaking said current-supply connections while current is flowing therein.

7. In a circuit-controlling apparatus, a plurality of electrical devices to be selectively energized, current-supply connections for said devices, record-controlled contact-making means for selectively completing connections to said devices during successive intervals, a source of alternating current, a full-wave rectifier for supplying current to said connections, said rectifier including a transformer and a pair of grid-controlled rectifier tubes connected to said transformer so as to operate on alternate half cycles of the alternating current from said source, said transformer including a secondary winding and said tubes having their anode elements connected to opposite terminals of said secondary winding, a condenser connected between the grid of one tube and the terminal of said winding opposite the terminal to which the anode of said tube is connected, a second condenser connected between the grid of the other tube and the terminal of said winding opposite the terminal to which the anode of said other tube is connected, whereby said tubes are rendered non-conductive by biasing voltages established across said condensers due to grid rectification in the tubes, and means for nullifying the effect of said biasing voltages to render said tubes conductive after the commencement of each said interval and for permitting the biasing voltages to become effective before the termination of each interval, whereby said devices are selectively energized without making or breaking said current-supply connections while current is flowing therein.

8. In a yarn-selecting apparatus, a plurality of electromagnets, connections for supplying current to said electromagnets, record-controlled means for selectively completing said connections during predetermined intervals, a source of alternating current, rectifier means including a grid-controlled rectifier tube for supplying current from said source to said electromagnets, and means for rendering said tube conductive after the commencement of each said interval and for rendering said tube non-conductive before the termination of each interval, whereby said electromagnets are selectively energized without making or breaking said connections while current is flowing therein.

9. In a yarn-selecting apparatus, a plurality of electromagnets, connections for supplying current to said electromagnets, record-controlled means for selectively completing said connections during predetermined intervals, a source of alternating current, a full-wave rectifier for supplying current from said source to said connections, said rectifier including a pair of grid-controlled rectifier tubes arranged to operate on alternate half cycles of the alternating current from said source, and means operable coordinately with said record-controlled means for varying the grid potential of said tubes so as to render the tubes operative after the commencement of each said interval and to render the tubes inoperative before the termination of each interval, whereby said electromagnets are selectively energized without making or breaking said connections while current is flowing therein.
10. In an electrical system, a source of alternating current supply, a load circuit to be supplied therefrom, a grid-controlled rectifier tube serially connected in said load circuit, means normally biasing the grid of said tube so as to render the tube non-conductive, contact-making means in said load circuit, means for closing said contact-making means during a predetermined interval, and means operable coordinately with said contact-making means for varying the bias on the grid of said tube so as to render the tube conductive after the commencement of said interval and to render the tube non-conductive before the termination of said interval, whereby the load circuit is energized without making or breaking the load circuit connections while current is flowing therein.
11. In a circuit controlling apparatus, an electrical device whose energization it is desired to control, current supply connections for said device, contact making means for completing said connections during a predetermined interval, a source of alternating current, rectifying means including a grid-controlled rectifier tube for supplying current to said connections, and means for rendering said tube operative after the commencement of said interval and for rendering said tube inoperative before the termination of said interval, whereby said device is energized without making or breaking said connections while current is flowing therein.
12. In a circuit controlling apparatus, a plurality of electrical devices to be selectively energized, current supply connections for said devices, contact making means for selectively completing connections to said devices during successive intervals, a source of alternating current, rectifying means including a grid-controlled rectifier tube for supplying current to said connections, and means for rendering said tube operative after the commencement of each said interval and for rendering said tube inoperative before the termination of each interval, whereby said devices are selectively energized without making or breaking said connections while current is flowing therein.
13. In a yarn-selecting apparatus, a source of alternating current supply, a load circuit to be supplied therefrom, said load circuit including a plurality of parallel branches, a plurality of electromagnets connected respectively in said parallel branches for energization from said source, a grid-controlled rectifier tube serially connected in said load circuit for supplying current from said source to said electromagnets, contact-making means for selectively closing
- 5 14. In an electrical system, a source of alternating current supply, a load circuit to be supplied therefrom, rectifying means including a grid-controlled rectifier tube serially connected in said load circuit for supplying current thereto, contact-making means for closing said load circuit during a predetermined interval, and means for rendering said tube operative after the commencement of said interval and for rendering said tube inoperative before the termination of said interval, whereby the load circuit is energized without making or breaking the load circuit connections while current is flowing therein.
15. In an electrical system, a source of alternating current supply, a load circuit to be supplied therefrom, said load circuit including a plurality of parallel branches, a plurality of electrical devices connected respectively in said parallel branches for energization from said source, rectifying means including a grid-controlled rectifier tube serially connected in said load circuit for supplying current thereto, contact-making means for selectively closing said parallel branches during successive intervals, and means for rendering said tube operative after the commencement of each interval and for rendering said tube inoperative before the termination of each interval, whereby said devices are selectively energized without making or breaking the load circuit connections while current is flowing therein.
- 20 16. In an electrical system, a source of alternating current supply, a load circuit to be supplied therefrom, a full-wave rectifier serially connected in said load circuit, said rectifier including a pair of grid-controlled rectifier tubes arranged to operate on alternate half cycles of the alternating current from said source, contact-making means for closing said load circuit during a predetermined interval, and means for rendering said tubes operative after the commencement of said interval and for rendering said tubes inoperative before the termination of said interval, whereby the load circuit is energized without making or breaking the load circuit connections while current is flowing therein.
- 25 17. In an electrical system, a source of alternating current supply, a load circuit to be supplied therefrom, rectifying means including a grid-controlled rectifier tube serially connected in said load circuit for supplying current thereto, means for causing the grid of said tube to draw current, means responsive to the grid current for biasing the grid of said tube so as to render the tube non-conductive, contact-making means for closing said load circuit during a predetermined interval, and means for rendering said tube conductive after the commencement of said interval and for permitting the grid bias to become effective before the termination of said interval, whereby the load circuit is energized without making or breaking the load circuit connections while current is flowing therein.
